[57] CLAIM

The ornamental design for the pill counter, as shown and described.

DESCRIPTION

FIG. 1 is a perspective view of the pill counter with the housing in the closed configuration and the separate thin planar elongate member in its receiving slot;

FIG. 2 is a top plan of FIG. 1;

FIG. 3 is a first side elevation of FIG. 1;

FIG. 4 is a first end elevation of FIG. 1;

FIG. 5 is a second end elevation of FIG. 1;

FIG. 6 is a second side elevation of FIG. 1;

FIG. 7 is a bottom plan view of FIG. 1; and,

FIG. 8 is a perspective view similar to FIG. 1 with the housing in the open configuration and the separate, thin, planar elongate member removed from its receiving slot.

FIG. 1

FIG. 2

FIG. 3

FIG. 4FIG. 5FIG. 6

FIG. 7

FIG. 8
